(57) **CLAIM**

The ornamental design for a mosaic solar lamp, as shown and described.

DESCRIPTION

FIG. 1 is a perspective view of the mosaic solar lamp of the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a bottom plan view thereof; and,

FIG. 7 is a top plan view thereof.

The broken lines represent that the interior surface of the mosaic lamp housing forms no part of the claimed design.
